REGULATING POUROUT FOR BOTTLES

Edward Sokolik, New Brighton, Minn.

Application October 27, 1949, Serial No. 123,840

6 Claims. (Cl. 222—479)

1

My present invention relates to improvements in pouring spouts for bottles more in particular for liquor or pharmaceutical bottles.

The principal object of the invention is to provide a pouring device provided with an air vent, and adapted for easily and precisely regulating, in the process of pouring, the volume of the pouring stream so as to fill a whisky glass or a pharmaceutical measure to the exact level without exercising any special effort or dexterity by the bartender filling the glass or pharmacist filling the drug measure.

A further object is to provide a pouring device with a gravity operative means for opening the pouring orifice as the bottle is being tilted and closing the orifice as the bottle is being uprighted, the means avoiding the pouring stream, and

Another object is to provide a pouring device with a gravity operative means for opening the air passageway as the bottle is being tilted and closing the passageway as the bottle is being uprighted.

Other objects and advantages will be apparent as the specification progresses.

Invention resides in the combination and arrangement of the pouring passageway and the air passageway and providing said passageways with gravity operative means for opening and closing said passageways in the process of pouring as the bottle is being tilted and uprighted, respectively, the means for opening and closing the pouring orifice being adapted to avoid the pouring stream.

On the drawings:

Fig. 1 is a side view of the device partly in section.

Fig. 2 is a plan view of the humped top edge of the device partly in section.

Fig. 3 is a view on line 3—3, Figure 1, looking in the direction indicated by the arrows.

Fig. 4 is a view on line 4—4, Figure 1, looking in the direction indicated by the arrows.

Fig. 5 is a view of the inner end of Figure 1.

Fig. 6 is a side view of a modified device partly in section.

Fig. 7 is a view on line 7—7, Figure 6, looking in the direction indicated by the arrows.

Fig. 8 is a plan view of the humped top edge of the device corresponding to Fig. 2 omitting the part in section.

Figs. 6, 7 and 8 illustrate one form of my pouring device, which includes a combined stopper-portion 17 and a spout-portion 18, either of suitable material.

The device may be made in a unitary body, or

5 it may be made in two sections (not shown) transversely joined by a slip or other joint. As illustrated, it is preferably made of lateral hemi-sections 11 and 12 sealably joined in a medial plane 13. This structure facilitates the manufacture of the device as the pouring passageway 22 and air passageway 15 are formed in complementary lateral hemi-passageways, one in each lateral section 11 and 12 and adapted to register at the medial plane 13 when the said sections 11 and 12 are sealably joined together.

10 A pouring passageway 22 and an air passageway 15 extend from end to end of the device, the air passageway 15 extending, with the device in a horizontal pouring position, along the top of, but separated from the pouring passageway 22 and being substantially of a uniform cross-sectional area throughout its length. These passageways 22 and 15 extend horizontally and normally parallelly superposed through the stopper-portion 17 and preferably of elliptical shape laterally, and preferably somewhat larger at their orifices 20 and 23, respectively.

15 In the spout-portion 18, the bottom 24 of the pouring passageway 22, in a horizontal pouring position, is deflected arcuately downwardly nominally twenty-five degrees and is humped at the top 25 thereof adjacent the stopper-portion 17 and sloping, generally in a straight line, 29 to the free end of the spout-portion 18. The lateral sides 28 of the pouring passageway 22 converge from the generally rounded orifice 26 thereof to the highest part 25 of the pouring passageway 22 adjacent the stopper-portion 17. This passageway 22 is transitioned from generally rounded orifice at the end to a narrow and high portion 14 in the form of a hump 25, the cross-sectional area throughout the said pouring passageway being substantially uniform, and in the process of pouring, a major change in the tilting of the bottle 30 is necessary to produce a minor change in the volume of the pouring stream requiring less precision and skill on the part of the bar-tender in serving liquors such as whiskey or on the part of the pharmacist in prescribing. The pouring is easily and precisely regulated and the conventional pouring of too little or too much is done away with.

20 The outer periphery of the spout-portion 18 is illustrated as being generally in symmetry with the inner periphery thereof and the air passageway 15 is illustrated as being formed in a beaded ridge 29 extending along the top of the vertical plane of said spout-portion 18.

25 The stopper-portion 17 is telescopically pro-

vided preferably with a resilient ferrule 21 of rubber, cork or the like, and may be provided with a flanged cap 19 which may be brimmed.

I prefer to deflect the free end of the spout-portion 18 downwardly nominally twenty-five degrees and to form the plane of the end of said spout-portion 18 at right angles to the axis of the free end thereof. This arrangement produces an overshot plane of about forty-five degrees to cooperate with the specific design of my gravity operative pivotally biased lid 16 to open and close the orifices 26 and 27 avoiding the pouring stream. To attain this mode of operation, I provide, as illustrated, my spout above the orifice thereof with a cantilever arm 31, provided with a pivot bore at the end thereof, and projecting forwardly from the end of the spout-portion 18 sufficiently to cooperate with the cantilever arms 32 to avoid the pouring stream in the process of tilting and arighting the bottle 30.

The arms 32 are parallelly spaced apart and project forwardly from the top of the front of the lid 16 straddling the arm 31 of the spout-portion 18. In view of the device being made in two lateral hemi-sections, it is preferable to provide the lid 16 with one arm and the spout with two arms, one on each lateral section. The arms 32 are provided with registering pivot bores registering with the bore of the arm on the spout and provided with a pivot 9. In a horizontal pouring position, the lid 16 will open at an angle of some 80 degrees depending on the relative weight of the lid 16 and its arm 32.

Figs. 1 to 5 illustrate a modified form of the invention. The only difference is that the air passageway 15, instead of extending from the hump 25 along the top 29 substantially in a straight line to the free end of the spout, is directed from the back of the hump 25 in the form of a reverse curve 34 emerging as an inlet air vent 36. The back of the hump 25 is preferably shaped in the form of a nose 33 to provide accommodation for the curve 34. This curved portion of the air passageway 15 not only serves as such passageway, but also serves as an enlarged runway 34 for a gravity operative ball valve 35, which is placed in before the sections are sealed together. This runway is provided at the inner end thereof with an air by-pass and ball stop 37. While this may be accomplished in various ways, I prefer to provide the runway with a ball valve 35 small enough to permit the air to by-pass the valve at the inner end, where I provide the stop 37 for the ball valve 35. At the outer end of the runway 34, I provide an annular seat for the ball 35 by reducing the diameter of the runway. This arrangement is peculiarly adapted to hemi-lateral construction of the device, as the ball is placed into the runway 34 before the hemi-lateral sections are sealed together.

The ball valve 35 rolls in the runway 34 from the annular seat that encompasses the air vent 36 to the stop 37 in the inner end opening the air vent 36 as the bottle 30 is being tilted and rolls from the stop 37 in the inner end to the annular seat and closes the air vent 36 as the bottle 30 is being arighted. It is to be understood that the form of my invention, herewith described and shown, is to be taken as a preferred example of the same, and that various changes in the shape, size and arrangement of the parts may be resorted to, without departing from the spirit of my invention, or the scope of the subjoined claims.

What I claim is:

1. In a pouring device of the character de-

scribed, the combination and arrangement in a body including a combined spout-portion and a stopper portion in combination with a bottle, of a pouring passageway extending through the body from end to end of said body and of an air passageway communicating the confines of the bottle with the atmosphere to admit a volume of air corresponding to the volume of contents being poured out, and with the body in a horizontal pouring position, the portion of the pouring passageway extending through the spout portion being arcuately downwardly deflected at the bottom thereof and humped at the top thereof adjacent the stopper-portion and sloping, generally in a straight line, to the free end of the spout-portion and diverging at the sides thereof to the free end of the spout-portion, thereby being transitioned from a generally rounded orifice at the free end to a narrow and high portion of the passageway adjacent the stopper-portion and being substantially of a uniform cross-sectional area throughout said spout-portion, and through the stopper-portion, of at least a corresponding cross-sectional area, the volume of the pouring stream being easily and precisely regulated as the stream flows through the narrow and high portion of the pouring passageway in the process of pouring, since a major tilting of the bottle is necessary to produce a minor change in the volume of the pouring stream; means for opening and closing the pouring orifice of the pouring passageway; and means for opening and closing the outer air orifice of the air passageway.

2. The structure defined in claim 1, in which, the body comprises two complementary lateral hemi-sections, each section having a sealing face with complementary hemi-portions of the pouring and air passageways formed therein, with a ball valve placed in one of the lateral hemi-air passageways of one of the sections and in sealing said sections together, said ball valve being sealed in the passageway, therebetween.

3. In a pouring device of the character described the combination and arrangement in a body including a combined spout-portion and a stopper-portion in combination with a bottle, of a pouring passageway extending through the body from end to end of said body, and of an air passageway communicating the confines of the bottle with the atmosphere to admit a volume of air corresponding to the volume of contents being poured out, and with the body in a horizontal pouring position, said air passageway extending along the top of the entire length of the pouring passageway, the portion of the pouring passageway extending through the spout-portion being arcuately downwardly deflected at the bottom thereof, and humped at the top thereof, adjacent the stopper-portion and sloping, generally in a straight line, to the free end of the spout-portion and diverging at the sides thereof to said free end, thereby being transitioned from a generally rounded orifice at the free end to a narrow and high portion of the passageway adjacent the stopper-portion and being substantially of a uniform cross-sectional area throughout said spout-portion, and through the stopper-portion, of at least a corresponding cross-sectional area, the volume of the pouring stream being easily and precisely regulated as the stream flows through the narrow and high portion of the pouring passageway in the process of pouring, since a major tilting of the bottle is necessary to produce a minor change in the volume of the pouring stream; means for opening and closing the ori-

fices of the passageways at the free end of the spout-portion.

4. In a pouring device of the character described, the combination and arrangement in a body including a combined spout-portion and a stopper-portion in combination with a bottle, of a pouring passageway extending through the body from end to end of said body, and of an air passageway communicating the confines of the bottle with the atmosphere to admit a volume of air corresponding to the volume of contents being poured out, and with the body in a horizontal pouring position, the portion of the pouring passageway extending through the spout-portion being arcuately downwardly deflected at the bottom thereof and humped at the top thereof adjacent the stopper-portion and sloping, generally in a straight line, to the free end of the spout-portion, and diverging at the sides thereof to said free end, thereby being transitioned from a generally rounded orifice at the free end to a narrow and high portion of the passageway adjacent the stopper-portion, and being substantially of a uniform cross-sectional area throughout said spout-portion, and through the stopper-portion of at least a corresponding cross-sectional area, the volume of the pouring stream being easily and precisely regulated as the stream flows through the narrow and high portion of the pouring passageway in the process of pouring, since a major tilting of the bottle is necessary to produce a minor change in the volume of the pouring stream; and the air-passageway extending from the free inner end of the stopper-portion through said stopper-portion and upwardly through the posterior portion of the spout-portion, substantially back of the hump of the pouring passageway and diverging therefrom in the form of a reverse curve emerging as an inlet air-vent, said curved portion of the air passageway being adapted to afford a runway for a gravity operative ball valve, said runway being adapted, at its inner end, to permit air to by-pass said ball-valve and at its inlet vent, provided with an annular seat encompassing said air vent and adapted to seat the ball valve, said ball valve rolling from said annular seat to the inner end of the runway and opening the air-vent as the bottle is being tilted, and rolling from said inner end onto said annular seat closing the air-vent as the bottle is being arighted; and means for opening and closing the pouring orifice of the pouring passageway.

5. In a device of the character described, the combination and arrangement in a body including a spout-portion and a stopper-portion in combination with a bottle, of a pouring passageway extending through the body from end to end of said body, and of an air passageway communicating the confines of the bottle with the atmosphere to admit a volume of air corresponding to the volume of contents being poured out, and with the body in a horizontal pouring position, said air passageway extending from the

free inner end of the stopper-portion through said stopper-portion, thence upwardly in the form of a reversed curve formed in the posterior portion of the spout-portion and emerging as an inlet air vent, said reversely curved portion of the air passageway being adapted to afford a runway for a gravity operative ball valve, said runway being adapted at its inner end, to permit air to by-pass said ball valve and at its inlet vent provided with an annular seat encompassing said air vent, and adapted to seat the ball valve, said ball valve rolling from said annular seat to the inner end of the runway and opening the air vent as the bottle is being tilted, and rolling from said inner end onto said annular seat closing the air vent as the bottle is being arighted.

6. In a device of the character described, the combination and arrangement in a body including a combined spout-portion and a stopper-portion in combination with a bottle, of a pouring passageway extending through the body from end to end of said body, and of an air passageway communicating the confines of the bottle with the atmosphere, to admit a volume of air corresponding to the volume of contents being poured out, and with the body in a horizontal pouring position, said pouring passageway, extending, at the bottom thereof, substantially horizontally straight in the stopper-portion and arcuately downwardly deflected in the spout-portion to the free end of said spout-portion, and at the top thereof, substantially horizontally straight through the stopper-portion curving uprightly in the posterior portion of the spout-portion and thence curving reversely in the form of a hump and sloping to the orifice at the free end of the spout-portion, the sides of said pouring passageway being laterally constricted, generally in the spout-portion adjacent the stopper-portion to the extent so that the cross-sectional area throughout the entire length of the pouring passageway is substantially of a corresponding cross-sectional area, the volume of the pouring stream being easily and precisely regulated as the stream flows through the narrow and high portion of the pouring passageway in the process of pouring, since a major tilting of the bottle is necessary to produce a minor change in the volume of the pouring stream.

EDWARD SOKOLIK.
